UNITED STATES PATENT OFFICE

157,311

UTILITY BOX

Alex Wiesen, New York, N. Y.

Application February 11, 1949, Serial No. 781

Term of patent 3½ years

(Cl. D58—12.6)

To all whom it may concern:

Be it known that I, Alex Wiesen, a citizen of the United States, residing at New York, in the county of New York and State of New York, have invented a new, original, and ornamental Design for Utility Box, of which the following is a specification, reference being made to the accompanying drawing, forming a part thereof.

In the drawing:

Fig. 1 is a perspective view of a utility box, showing my new design (in closed position);

Fig. 2 is a top view;

Fig. 3 is an end view;

Fig. 4 is a rear view;

Fig. 5 is a front view;

Fig. 6 is a sectional view on line 6—6 of Fig. 5;
and

Fig. 7 is a perspective view of the box in open position.

I claim:

The ornamental design for a utility box, as shown.

ALEX WIESEN.
